FOUNTAIN PEN

Filed March 11, 1926

INVENTOR

H. Dudley Kellogg Jr.

UNITED STATES PATENT OFFICE

HOSFORD DUDLEY KELLOGG, JR., OF HAVERFORD, PENNSYLVANIA

FOUNTAIN PEN

Application filed March 11, 1926. Serial No. 93,933.

My invention relates to improvements in fountain pens and has for its object to provide a pen of the type generally known as a stylographic pen, in which a positive flow ⁵ of the writing fluid at and around the point is assured.

Further, said invention has for its object to provide a pen in which the ink or writing fluid is delivered to the point through an annular or ring-shaped opening above the point, so that the fluid flows around the point instead of through channels within the point.

Further, said invention has for its object to provide a pen having a nozzle inside which ¹⁵ the ink is carried to the point, and which may be either fixed in position with reference to the point of the pen or may be adjustable to increase or decrease the opening through which the fluid flows onto the point, thus ²⁰ regulating the rate of flow.

Further, said invention has for its object to provide a point member of cylindrical or conical shape or both and with or without fluid channels or grooves cut upon its surface to draw the writing fluid down to, and surrounding, the point.

Further, said invention has for its object to provide a nozzle member of varied cross-section, and slotted or drilled in varied manner to admit air into the fluid reservoir and to promote the flow of fluid to the point.

Further, said invention has for its object to provide a pen having a vented nozzle member which may be screwed back into the barrel to partially or fully close the air vent openings thereby regulating the rapidity of ink flow through the nozzle and to the point.

Other objects and advantages of the device are described and will be apparent hereinafter.

To the attainment of the aforesaid objects my invention consists in the novel details of construction and in the combination, connection and arrangement of parts hereinafter ⁴⁵ more fully described and then stated in the claims.

In the accompanying drawings,

Figure 1 is a longitudinal section through the axis of the pen showing the barrel and ⁵⁰ cap, nozzle and point.

Figure 2 is an exterior view of the nozzle member.

Figure 3 is an end view of the point member.

Figure 4 is a longitudinal view of the ⁵⁵ point member.

Figure 5 is a longitudinal section through the axis of the assembled pen in which both the point and nozzle members are provided with threads and screwed into the barrel, ⁶⁰ as contrasted with Fig. 1, in which the point member is shown fixed in place with a smooth tapered fit, while only the nozzle is screwed to its position. Fig. 5 also shows an alternate construction for the tip of the nozzle, ⁶⁵ which is cut in toward the point instead of outward away from it, forming a Venturi-shaped outlet orifice.

Figure 6 is a longitudinal view of the point member provided with a threaded pedestal to ⁷⁰ screw into the barrel and with capillary lines cut along the face of the cylindrical and conical surfaces to the tip. These capillary lines greatly promote the flow of ink downward from the nozzle ink reservoir.

Figure 7 is an exterior view of the nozzle member provided with a slot adjacent to, and running back from, the fluid opening at the point, and with a groove (or slot) to admit air cut back along the tapered shank ⁸⁰ fitting into the barrel.

Figure 8 is a sectional view on the axis of the point showing the construction adapted to the attachment of a rubber sack for a self-filling design. A more solid construction for the rod-like or stem portion of the point member is also shown, with one of the variously formed conical surfaces which may be employed, extending from the thicker material at the stem, to the tip.

In said drawings, Figures 1 to 4 give the basic construction on which the variations given in Figures 5 to 8 inclusive, are dependent. But the construction of the point and nozzle members shown in the latter figures operates more perfectly than the more general construction shown in Figures 1 to 4 and are therefore stated as a special case and included in this specification. In the drawings, 1 is the barrel, 2 is the main ink res- ⁹⁰ 100

ervoir, and 3 is the cap. 4 is the nozzle member, which may be either threaded at 5 and screwed varying distances into the barrel, or in case the variable feed feature is not desired, may be set in a fixed position with the tapered shank shown in Fig. 7. The nozzle member may be set either in the inside or outside of the barrel, the former case only being shown on the drawing, as the latter mentioned arrangement does not alter the fundamental construction. The nozzle may be machined or formed to a smooth finish on its inside surface 6, or may be serrated or grooved.

15 The discharge end of the nozzle 7 is so formed that when the nozzle is fully screwed into the barrel, it contacts with the point member 8, thus closing the orifice and cutting off the ink flow. Conversely, the nozzle may be screwed out to within a reasonable distance of the end of the point 9, thus greatly enlarging the annular opening 10 and permitting a greater volume of ink to flow. By varying the position of the nozzle between these limits a wide range in the rate of flow of the writing fluid can be obtained.

20 The point member consists of a pedestal 11, which may be set in place in the barrel with a tapered fit as shown in Fig. 1, or 25 screwed in place as shown in Fig. 5. The pedestal has ample channels 12, Figures 3 and 4, running longitudinally with reference to the point member, through which the ink flows from the reservoir into the nozzle chamber 13, and thence through the annular orifice 10 to the tip 9. Continuous with the pedestal 11 is the stem 8, which narrows down at the seat 14 to the tip 9. The seat 14 is so called because it is here that the nozzle 4 contacts with the point member to cut off the ink flow when the nozzle is fully screwed into the barrel. The point member may be supported on its pedestal within the nozzle member, effecting a desirable reduction in over-all 40 length of the pen and providing more space within the barrel for the conventional rubber ink sack.

45 In Fig. 2, the discharge end of the nozzle 7 is cut back and outward away from the point. In Fig. 5, the discharge end 7 is cut back and inward from the point, a construction which alters the operating characteristics of the pen. Needless to say, a delicate fluid balance exists between the length, shape and taper of the inner surface 6 of the nozzle and nozzle chamber 13, the outer surface of the point member at the stem 8, the seat 14 and the tip 9, and the construction at the nozzle discharge opening 7.

50 An important detail of construction applied to the point member is shown in Figures 5 and 6, in which capillary lines 15 are cut into the stem 8. These capillary lines are preferably continued across the writing tip, and greatly assist in drawing the ink down to

the end of the point. A hexagonal or a lobe-shaped cross-section, or any contour giving ridges and hollows running longitudinally of the stem will give the same general effect. Fig. 8 is a construction with heavier stem 70 which permits a sharper fall from the stem 8 to the tip 9 and facilitates the flow of ink at and near the tip.

55 The preferred form of bearing for the pedestal 11 inside the barrel is furnished by a three-surface support. This leaves large openings in the periphery of the pedestal for the flow of ink from the reservoir to the point, while providing substantial support for the point member. An extension 17 over which 80 the rubber sack for a self-filling type of pen can be inserted, is shown in Figure 8.

Fig. 7 shows two details of construction applied to the nozzle member. In this case the nozzle sets inside the barrel with a tapered fit, applicable where variable adjustment of the ink flow is not desired. A slot 18 is here shown running back from the tip, to open the ink chamber inside the nozzle and effect desired changes in the fluid flow to and at 90 the point. A groove, or slot, 19, is applied to the shank 5 to permit air to be drawn up into the barrel, thus venting the nozzle ink chamber and permitting the ink to flow freely out the nozzle orifice to the point. It is not 95 intended to convey the impression that the nozzle or point members need necessarily have uniform conical or cylindrical surfaces, as herein shown for simplicity and clarity in the drawings. It should be understood the 100 surfaces (6, 13, 8, 14, 9 and 7) mentioned in an earlier paragraph, which are in contact with the writing fluid, may have any curved, angular or irregular surface relationship to each other permitted within the sense of this 105 invention.

Having thus described my said invention, what I claim and desire to protect by Letters Patent of the United States is:—

1. In a stylographic pen, in combination, 110 a barrel for the ink supply, a rigid point member supported by a longitudinally channelled pedestal within the barrel and with a solid core stem tapering to the writing tip, said point member being surrounded below its 115 pedestal by a nozzle member supported in, and having longitudinal air vents extending within, the barrel and tapering internally and externally to an outlet orifice in juxtaposition to, and partially enshrouding the end of said 120 writing tip.

2. In a stylographic pen the combination with a barrel adapted to contain an ink supply, of a longitudinally channelled pedestal 125 disposed within an end thereof, a rigid point member carried by the pedestal, a nozzle member surrounding said point member, tapering internally and externally toward the end thereof and providing an orifice hav- 130

- ing a sharply edged minimum diameter adjacent to the end of the point member.
3. A nozzle member for a stylographic pen having longitudinal air vents cut in the supporting surface on the upper end and tapering internally and externally therefrom to a discharge orifice, said orifice having a sharply edged minimum diameter in juxtaposition to the nozzle outlet end.
- 10 4. A vented nozzle member for a stylographic pen, tapering internally and externally from the upper supporting end to the discharge orifice, the end surface of which discharge orifice is cut back internally forming a concave outlet opening.
5. A vented nozzle member for a stylographic pen, tapering internally and externally from the upper supporting end to the discharge orifice, the end surface of which discharge orifice is cut back externally forming a convex outlet surface.
- 20 6. A vented nozzle member for a stylographic pen, tapering internally and externally from the upper supporting end to the discharge orifice, thereby forming a continuous ink chamber open at both ends, said discharge orifice being slotted with longitudinal slots cut thru the shell of said nozzle member to the ink chamber within.
- 25 7. In a stylographic pen comprising a barrel and a solid writing point member connected thereto, the combination therewith of a longitudinally adjustable nozzle member surrounding the point member and having
- 30 air vents connected to the barrel, so that the nozzle member may be moved up inside the barrel and the vents to the atmosphere may be thereby varied from full open to closed position.
- 35 40 In testimony whereof, I have hereunto set my hand this 10th day of March 1926.
